UNITED STATES PATENT OFFICE.

HENRY E. SHAFFER, OF ROCHESTER, NEW YORK, ASSIGNOR TO THE
SHAFFER LAMP COMPANY, OF SAME PLACE.

LAMP.

SPECIFICATION forming part of Letters Patent No. 546,435, dated September 17, 1895.

Application filed July 16, 1894. Serial No. 517,626. (No model.)

To all whom it may concern:

Be it known that I, HENRY E. SHAFFER, of Rochester, in the county of Monroe and State of New York, have invented a certain new and useful Improvement in Lamps, of which the following is a specification.

My improvement relates to center-draft lamps; and the invention consists in the construction and arrangement of parts herein-
10 after described and claimed.

In the drawings, Figure 1 is a central vertical section of the lamp. Fig. 2 is a cross-section of same in line $\alpha\alpha$ of Fig. 1.

A indicates the fount, which may be of any
15 desired form.

B is the base; C, the burner, and D the wick-tube, the latter extending some distance below the fount, as shown. The wick rests outside this wick-tube and is exposed directly
20 to contact with the oil throughout the fount.
a is the lower section of an exterior tube, and d an upper section of such exterior tube. The lower section a extends from the bottom of the fount down as far as the lower end of
25 the interior tube D, and is connected therewith so as to close the space between the two tubes and form a well or chamber below the bottom of the fount, which well or chamber receives the lower end of the wick, also oil
30 from the fount. Said chamber stands outside the interior tube, by which means the wick extends in a straight length from bottom to top, thereby insuring freedom of movement to
35 the wick in moving up and down. The upper section d of the exterior tube forms an integral part of the burner C, and is removable with the latter from the top of the fount. In the drawings the lower end of the burner C is shown fitted removably in a circular flange
40 at the top of the fount. The section d is located at such a distance from the interior tube D that the wick passes loosely through the space between the tubes, by which means it is moved freely up to supply combustion,
45 and in applying the wick in place it is entirely removed from the lamp, leaving the whole space open, so that the wick can be readily inserted over the interior tube and moved downward. The space between the lower
50 section a and the interior tube is also of such size that when the wick is inserted in the

lamp its lower end passes readily down into the oil-chamber below the fount. By this construction not only is the wick readily inserted and removed, but by making the break 55 in the exterior tube heat is prevented from passing downward through said exterior tube. The advantages are obvious over those lamps having two tubes extending entirely through the fount, in which case it is very difficult to 60 insert the wick, and heat is conducted directly down into the fount. This invention is equally applicable to those center-draft lamps in which the upper tube-section d is removable from the top of the fount inde- 65 pendently of the burner C.

The exterior tube-section a is provided with a bead p, and the tubular stem of the hollow base B is extended up to the bead, covering the lower end of the wick-tube and secured 70 thereto. Above the bead is a brace J, preferably having holes through its sides through which air can pass to cool the tube. In high lamps two beads may be used, the base extending up to the first one and the brace ex- 75 tending upward from the second one. The tubes are secured to the base by solder k or any other suitable means. The space of the tubes and fount covered by the brace J is imperforate and closed, and none of the air 80 which passes through the brace passes upward into the lamp, but simply surrounds the tubes and fount and circulates in the inclosed space and keeps the parts cool.

By the construction above described, the 85 base simply incloses the lower end of the oil and wick chamber, and the latter is exposed to cold air both above and below the attachment of the base thereto and the use of tie rods and other complicated parts is avoided. 90

Having described my invention, I do not claim simply and broadly double tubes extending below the bottom of the fount, nor do I claim double tubes extending through the fount and inclosing the wick, but 95

What I claim as new, and desire to secure by Letters Patent, is—

1. A central draft lamp having an interior wick tube extending from the burning point to some distance below the fount, an exterior 100 wick tube in two sections, the upper section extending to the top of the interior tube and

removable therefrom, the lower section extending from the bottom of the fount and connected with the interior wick tube to form a wick and oil chamber below the fount, the two exterior wick tube sections being separated in the fount to directly expose the wick to the oil, and a hollow base having a tubular stem embracing a portion of the exterior wick tube and secured thereto, the said exterior wick tube being exposed to the air above and below the tubular stem of the base, as herein shown and described.

2. A central draft lamp having an interior wick tube extending from the burning point to some distance below the fount, an exterior wick tube in two sections, the upper section extending to the top of the interior tube and removable therefrom, the lower section extending from the bottom of the fount and connected with the interior wick tube to form a wick and oil chamber below the fount, the two exterior wick tube sections being separated in the fount to directly expose the wick to the oil, the lower exterior wick tube being provided with a bead, and a hollow base having a tubular stem embracing a portion of the exterior wick tube and abutting against the bead, the said exterior wick tube being exposed to the air above and below the tubu-

lar stem of the base, as herein shown and described.

3. A central draft lamp having an interior wick tube extending from the burning point to some distance below the fount, an exterior wick tube in two sections, the upper section extending to the top of the interior tube and removable therefrom, the lower section extending from the bottom of the fount and connected with the interior wick tube to form a wick and oil chamber below the fount, the two exterior wick tube sections being separated in the fount to directly expose the wick to the oil, a hollow base having a tubular stem embracing a portion of the exterior wick tube and secured thereto above the lower end thereof to expose the lower end of the wick tube to the air, and an exterior brace above the base joined at one end to the exterior wick tube and at the other to the fount, as shown and described and for the purpose specified.

In witness whereof I have hereunto signed my name in the presence of two subscribing witnesses.

HENRY E. SHAFFER.
